UNITED STATES PATENT OFFICE

GLENN E. McFADDEN, OF DETROIT, MICHIGAN, ASSIGNOR TO LINCOLN MANUFACTURING COMPANY, OF DETROIT, MICHIGAN, A CORPORATION OF MICHIGAN

DESIGN FOR A CHANDELIER OR ANALOGOUS LIGHTING FIXTURE

Application filed September 5, 1929. Serial No. 32,869. Term of patent 7 years.

To all whom it may concern:

Be it known that I, GLENN E. McFADDEN, a citizen of the United States, residing at Detroit, county of Wayne, State of Michigan, have invented a new, original, and ornamental Design for a Chandelier or Analogous Lighting Fixture, of which the following is a specification, reference being had to the accompanying drawing, forming part thereof.

Fig. 1 is a front elevation of my chandelier or analogous lighting fixture.

Fig. 2 is a cross-sectional view taken on the

line 2—2 of Figure 1, of the structure illustrated in Fig. 1 wherein the decoration appears in solid line over only one of the candle cups, it being understood that such decoration is repeated over corresponding parts of the structure shown in dotted outline.

I claim:

The ornamental design for a chandelier or analogous lighting fixture, as shown and described.

GLENN E. McFADDEN.
